CLAIM

The ornamental design for a bathtub tray, as shown and described.

DESCRIPTION

FIG. 1 is a top right front perspective view of a bathtub tray showing our new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof; the left side elevational view being a mirror image.

FIG. 1
